UNITED STATES PATENT OFFICE.

HAROLD T. MARTIN, OF EAST ORANGE, NEW JERSEY, ASSIGNOR TO WESTERN ELECTRIC COMPANY, INCORPORATED, OF NEW YORK, N. Y., A CORPORATION OF NEW YORK.

DESIGNATION DEVICE.

Application filed August 23, 1924. Serial No. 733,716.

To all whom it may concern:

Be it known that I, HAROLD T. MARTIN, a citizen of the United States, residing at East Orange, in the county of Essex, State of New Jersey, have invented certain new and useful Improvements in Designation Devices, of which the following is a full, clear, concise, and exact description.

This invention relates to apparatus for designation purposes, and more particularly to designation means for correlative associating the components of one group of apparatus with corresponding or related components of another group.

The object of the invention is to furnish convenient and inexpensive means for aiding an operator in one telephone exchange to associate a particular call circuit key connecting that exchange to another exchange with the proper group of trunks that connect that exchange to the other exchange.

A feature of this invention resides in the provision of a designation plate, preferably rhombus in shape, having a hole through which apparatus, such as a call circuit key, may be passed.

In the arrangement now usually employed, each call circuit key has the exchange it connects with, marked on the flat top key surface thereof. Inasmuch as one operator's position may have direct or multiplied connecting facilities with as many as one hundred or more other exchanges, there would be as many call circuit keys at her position, as the number of exchanges she could connect with. For each call circuit key at an operator's position, there is also a corresponding group of trunks terminating in jacks at that position, the trunks serving to connect subscribers to the same distant exchange that the call circuit key connects with. The trunks each properly marked are arranged under panels, each panel being numbered. Therefore, in order to facilitate operation, it is essential that the operator be aided in associating a particular call circuit key connecting to a distant exchange with the proper numbered panel which contains the corresponding trunk jacks that connect to the same distant exchange. At the present time this is accomplished by

placing over the entire bank of call circuit keys, numbering as many as one hundred and twenty, a template, usually of hard oiled white rope paper, bearing the number of each trunk group panel adjacent to the hole for the associated call circuit key button. This scheme, however, is expensive and entails loss of time, for whenever a change is made in the call circuit layout and a consequent regrouping of the keys takes place, a new template must be furnished, and operation delayed at the position affected until replacement with the new template is made.

The present invention is designed to avoid this waste and instead to furnish a convenient means for associating any call circuit key with its proper trunk group panel number, without the aid of a template for an entire group of keys, and to practically eliminate delay in operation when a key is given a new number.

Other features of the invention will more readily appear from the following description in conjunction with the accompanying drawing in which Fig. 1 shows a partial view of a bank of call circuit keys sufficient to illustrate the invention. Figs. 2 and 3 respectively are detail views of the number plate for each individual key and of an end detail used with a row of number plates.

An individual designation or number plate, is provided for each key. Each key has the exchange it connects with, as X, marked on its flat top surface. The individual number plate is rhombus in shape, with a hole through which the key, for example X, passes to keep it in place. To maintain a plurality of such individual number plates in alignment, end strips, 2, are secured to the key tops, 4, by screws, 5. The end strips are designed to fit the shape of the adjacent number plate and the edge of the key top. Further, to securely maintain in alignment a row or a plurality of rows of number plates, so used, and placed side by side, metal key spaces, 3, are provided. The metal spaces are placed on each side of a row or a plurality of rows of number plates, extend the length of the row of keys, that is from one edge of the key top 6 to the opposite

edge 7, and prevent the number plates from moving in a lateral direction. The metal spaces themselves are snugly held between the adjacent lengthwise edge of the key top, 5 9, and the side of the receptacle which holds the key top, as, for example, the edge of the operator's desk into which the key top rests. Prongs 8, are provided to maintain the tops 10 of the spaces and the tops of the number plates at a uniform level.

The number plate will have stamped thereon a number for example 25, which indicates the number of the panel containing the trunks leading to the exchange, for example 15 X, served by its associated key, passing therethrough.

Therefore, if an operator desired a connection with exchange X, she would press key X, noting on the associated number 20 plate that the trunks leading to exchange X could be found at trunk group panel number 25. Upon being assigned a trunk by the responding operator at exchange X, she would look to panel 25 and plug in at the 25 assigned trunk. If calling exchange Y, she would note that trunks leading thereto could be found at panel 14, etc.

In case the needs of service required regrouping of trunks and change in the call 30 circuit layout, each individual number plate affected could be removed by merely pulling out the key top which fits in the hole, and placing a number plate with the desired trunk group panel number, in its stead. The 35 key top would be reinserted in the hole of the new number plate, and the key would again be ready for service. For example, if in a regrouping, exchange X were to be assigned trunks in panel 14 and exchange Y 40 assigned trunks in panel 25, key tops X and Y would be pulled out, the number plates interchanged, and the key tops reinserted.

It may be seen, therefore, that the call 45 circuit key buttons may be given interchangeably any desired trunk group panel number. The number plates are interchangeable, may be used over and over again, and the keys affected easily renumbered without affecting those whose trunk assignment remains unchanged.

The number plates 1, and end strips 2, may be made of bakelite, hard rubber, wood, etc. The spaces, 3, may be made of metal or other suitable material.

55 While the invention, as herein described, is particularly applicable to the association, by such designation, of call circuit keys with their proper trunk group panels, nevertheless, its use is not so limited. Thus such 60 designation means may be used to associate selection equipment, as selectors or switches, with connecting lamps, keys, etc., or used in testing or tabulating systems, requiring association of components in one group of 65 means with components of another.

What is claimed is:

1. A designation plate, rhombus in shape, with a character thereon, containing a hole centrally located with respect to the sides thereof. 70

2. A designation plate, containing a hole, through which apparatus may be passed, and a number inscribed thereon to designate said apparatus.

3. In combination, a plurality of designation plates, substantially rhombus in shape, with a hole through each, through which apparatus may be passed, and end strips for maintaining said plates in alignment, whereby a row of said plates placed adjacent one 80 to the other with an end strip at each extremity of said row, appears substantially rectangular in shape, and acts as a designation strip for a row of apparatus passed through said holes. 85

4. In combination, a plurality of designation plates of insulating material in consecutive arrangement, each substantially rhombus in shape, with a hole through each, end strips made of substantially the same 90 material at both ends of said plurality of plates, and metal strips kept level with the surface of said plurality of plates and on each side thereof, for maintaining a row of 95 said plates in alignment.

5. A designation device, comprising plates, with a hole in each, through which apparatus may be passed, an identification mark on each said plate for designating apparatus passing therethrough, said apparatus in turn 100 serving to keep the plate through which it passes in position.

6. A designation device comprising a plurality of identically shaped plates with a hole in each through which apparatus may 105 be passed, an identification mark on each said plate, said apparatus being constructed and arranged to keep said plates in position.

7. A designation device, comprising a plate, with a character thereon, through 110 which apparatus may be passed to fix the position thereof.

8. A designation device, comprising a plurality of plates, with a hole in each through which apparatus may be passed, an identification mark on each said plate, said plates being interchangeable. 115

9. A designation device, comprising a plurality of plates, each rhombus in shape, with a hole through which apparatus may be 120 passed, an identification mark on each said plate, said plates being interchangeable.

10. A designation device, comprising a plurality of plates, with a hole in each through which apparatus may be passed to 125 keep each said plate in position, an identification mark on each said plate to designate said apparatus passing therethrough, said plates being interchangeable.

11. In combination, switching means com- 130

prising a base, a support mounted on said base, a plurality of sets of contact springs mounted on said support, said base having a plurality of apertures formed therein corresponding in number and position to said sets of contact springs, a plurality of designation plates placed on said base each having an aperture formed therein, and a plurality of key plungers passed through the

apertures of said designation plates and 10 said base, said plungers being constructed and arranged to actuate said contact springs and to hold said designation plates in position.

In witness whereof, I hereunto subscribe 15 my name this 21st day of August A. D., 1924.

HAROLD T. MARTIN.
